TAPE-SERVING DEVICE

Alfred P. Krueger, Stratford, and Oscar P. Erhardt, Derby, Conn., assignors to Derby Sealers, Incorporated, Derby, Conn., a corporation of Connecticut

Application April 16, 1947, Serial No. 741,898

18 Claims. (Cl. 164—84.5)

1

This invention relates to tape-dispensing machines, and more particularly to a machine adapted for dispensing pressure sensitive, so-called "scotch", tape, or tape which is clingable or tacky upon one of more surfaces without the addition of a liquid.

The dispensing of scotch tape has presented certain problems in that one surface of the tape is tacky and will tend to cling to any object with which it comes in contact, and, as the tape is usually wound upon a roll with the tacky surface of one layer in engagement with the non-tacky surface of the under layer, it requires an appreciable effort to draw the tape from the roll. Due to the fact that the tape tends to cling to any object with which it comes in contact, it is usually necessary, if the tape is drawn from the roll by some mechanical feeding means, to provide a stripper of some kind to strip the tape from the feeding means. Where the tape is grasped by the fingers and drawn from the machine, this stripping means should be so arranged as to provide a free projecting end portion of tape which can readily be grasped by the operator.

It is contemplated by the present invention to provide a tape-dispensing machine in which the tape is drawn from the roll or from the machine by the operator who grasps the free end of the tape and exerts a pull thereon. In addition, however, there is provided a feeding member or drum to which the tape clings and which is adapted when rotated to draw the tape from the roll, the rotation of the feeding member or drum being effected by the pull of the operator on the free end of the tape. As will be hereinafter explained, the mechanism is so arranged to reduce the effort required to draw the tape from the supply roll.

There is also provided in the mechanism disclosed a severing member against which the tape may be torn off, to which severing member is imparted an advancing movement during the feeding operation and a reverse or receding movement after the completion of the feeding operation so as to expose a free end of the tape and render it accessible to be grasped by the operator. Means are provided to lock the severing member against movement during the severing operation and, at the same time, to provide for a previous forward movement of the feeding member to any extent necessary in order that the desired quantity of tape may be withdrawn from the roll and severed.

It is also contemplated in the present invention to provide a stripper member which will

2

cooperate with the feed member or drum, so that the free end of the tape will be positively stripped from the drum and, at the end of a cycle of operations, will extend freely from the drum where it is in an accessible position to be grasped by the operator.

One object of the present invention is to provide a new and improved device for dispensing tape.

10 A further object of the invention is to provide a new and improved device for dispensing tape having the feed drum mounted on a moving or oscillatable arm, and a severing member or tear-off blade also mounted on this arm and movable with respect to the arm.

15 A still further object of the invention is to provide a new and improved tape dispensing machine of the character described in which the severing member or tear-off blade will be moved forwardly during the feeding operation, and will be locked in its forward position in order that the tape may be readily torn off against the blade.

20 Still another object of the invention is to provide a tape-dispensing machine of the character described having the feed stripper mechanism mounted on the oscillatable arm, the stripper mechanism being actuated by the movement of the arm, so that, at the end of the return stroke of the latter, the stripping means will be moved to strip the free end of the tape from the feeding means.

25 To these and other ends the invention consists in the novel features and combinations of parts to be hereinafter described and claimed.

30 In the accompanying drawings:

Fig. 1 is a front elevational view of a tape-dispensing machine embodying our invention;

Fig. 2 is a side elevational view thereof;

40 Fig. 3 is an enlarged side elevational view of certain of the parts of the mechanism with the supply roll of tape removed and with the oscillating arm shown in a forward position;

Fig. 4 is a view similar to Fig. 2 with the oscillating arm shown in its rearward position at the end of the return stroke; and

Fig. 5 is a detail sectional view on line 5—5 of Fig. 1.

To illustrate a preferred embodiment of our invention, we have shown in the accompanying drawings a tape-dispensing machine comprising a frame in the form of a plate 10, the plate being supported in upright position from the base 11 which may rest upon or be secured to a suitable support. Secured to the frame member 10 is a

shaft 12, and upon this shaft is rotatably mounted a relatively large gear 13, which, as will be explained later, serves as a rack rather than as a gear. Rotatably mounted on the shaft 12, as shown more especially in Fig. 2, this gear is restricted from rotation in a counterclockwise direction by a pawl 14 pivoted to the frame member 10 at 15 and overweighted at its rear end or tail portion 16, this end of the pawl resting upon a pin 17.

Also rotatably mounted on the shaft 12 is an arm 19, this arm serving as a carrier member for the feeding means 20, the latter being in the form of a drum and consisting of spaced disk-like elements 21 which are serrated on their peripheral edges, so that the tacky surface of the tape will cling thereto only to a certain degree and be drawn from the supply roll, as hereinafter explained. The feed drum 20 is secured to a shaft 22 which is rotatably mounted in the arm 19 and projects therefrom at the side opposite the feed drum. A pinion 23 is mounted on the projecting end of this shaft, the teeth of which are in mesh with those of the gear 13. From the foregoing, it will be apparent that, when the arm 19 is rocked in a counterclockwise direction, as shown in Fig. 2, the pinion 23 will be drawn over the periphery of the gear 13, and, as the latter is locked against movement in this direction by the pawl 14, the pinion will be rotated and effect the rotation of the feed drum 20.

A spring 25 is coiled about a spacing collar 26 on the shaft 12, one end of this spring being secured at 27 to the arm 19 and the other end being secured at 28 to a plate 29 secured at 30 to the frame member 10, this plate having an offset portion 31, so that it stands in spaced relation with the frame member 10 and upon the side of the arm 19 opposite the frame member. The spring 25 tends to return the arm 19 to its rearward position, shown in Fig. 2, after it has been moved from this position.

Also rotatably mounted on the shaft 12 is a holder 32 to support the supply roll of tape 33. As shown in Fig. 1, the roll of tape lies substantially in the same vertical plane as the feed drum 20, so that the free end 34 of the tape (Fig. 2) may be trained around the feed drum and project therefrom, as shown at 35, so that it may readily be grasped by the fingers of the operator.

On the side of the arm 19 adjacent the frame member 10 is pivoted an arm 37 (Fig. 5) which carries a pawl 38 in engagement with the teeth of the pinion 23, this pawl being urged toward the pinion by the spring 39 secured at one end to the arm 37 and at the other end to the carrier 19. Thus, when the arm 19 is moved in a counterclockwise direction, as shown in Fig. 2, or a clockwise direction, as shown in Fig. 5, the pinion will be free to rotate on the teeth of the rack gear 13, the latter being held against rotation. When, however, the arm 19 is returned to its rearward position by the spring 25, the pinion 23 will be held against rotation and will effect rotation of the gear 13 in a clockwise direction, as shown in Fig. 2, which rotation will be permitted by the pawl 14. Thus, as the pinion 23 does not rotate on the reverse or rearward movement of the arm 19, there is no rotation of the feed drum 20 at this time.

In order that measured lengths of tape may be dispensed from the machine, a stop member 40 is adjustably secured at the upper front portion of the frame member 10 by a set screw 41, this

stop member being provided with a portion 42 overhanging the gear 13, so that it will be engaged by the pinion 23 when the latter is moved forwardly in a feeding direction. As shown in Figs. 2 and 3, the upper forward portion of the frame member 10 is rounded to conform to the periphery of the gear 13, so that, as the stop member is moved over this rounded portion of the frame, the portion 42 will lie close to the periphery of the gear and be in position to be engaged by the pinion.

A severing member in the form of a tear-off blade 44 is mounted upon the arm 19 adjacent the periphery of the feed drum, and a resilient stripping blade 45 is secured to the under surface of this member which, by the inherent resilience of the stripping blade, will strip the tape from the blade if the tape tends to adhere thereto after a severing operation. The blade 44 is carried by an arm 46 pivoted to the member 19 at 47, so that the blade may rock with respect to the arm and with relation to the axis of the feed drum 20. A spring 48 secured at one end to the member 19 as at 49 and secured at its other end to the arm 46 tends to urge the latter in a counterclockwise direction about the pivot 47, as shown in Fig. 3, when the arm 19 is in a forward position. However, at the end of the return movement of the arm 19, or when the latter is in its rearward position, a cam shoulder 50 on the lower end of the arm 46 will strike a cam member 51 on the plate 29 to move the arm 46 in a clockwise direction about its pivot 47 to the position shown in Fig. 2. It will be apparent that in this position the severing member 44 is moved rearwardly with respect to the axis 22 of the feed drum so as to expose a larger portion of the tape engaged with this drum, and particularly expose the free end 35, so that it may be grasped with ease. When, however, the arm 19 is moved forwardly in a feeding movement, the severing member 44 will also be moved forwardly to the position shown in Fig. 3, so that the tape will be severed at a point forwardly of the feed drum, thus leaving the free end 35 when the severing member is returned to the position shown in Fig. 2.

In order that the severing member 44 will be held in position during the severing operation and not move rearwardly against the tension of the spring 48 by pressure of the tape against the severing edge, we have provided the latch member 52, which is secured to a hub 52^a rotatably mounted upon the shaft 12. This latch member is provided with a flange 53 having thereon a latch dog 54 adapted to engage over a pin 55 secured to a tailpiece 56 forming the lower end of the arm 46. It will be apparent that the flange 53 extends across the edge of the arm 19, so that the latch member will be moved forwardly with the arm 19. The rearward or clockwise movement of the latch member is limited, however, by engagement of its edge with the stop 57 on a plate 58 secured to the plate 29 but lying on the opposite side of the arm 19. A spring 60 secured at one end to the arm 19 at a point opposite the pin 27 and secured at the other end as at 61 to the latch member 52 tends to urge the flange 53 toward the arm 19. It will be noted that in the rearward position of the arm 19, as shown in Fig. 2, the flange 53 will be held in a position spaced from the forward edge of the arm 19 by the stop 57, and the pin 55 on the arm 56 will lie in a position adjacent the upper edge of this flange. When the arm 19 is moved in a counterclockwise

direction or in the direction to feed tape, the cam surface 50 will be moved away from the surface 51, and the arm 46 will be moved in a counter-clockwise direction about its pivot 47 relatively to the arm 19 until the pin 55 strikes against a shoulder 63 on the forward edge of the arm 19 which will arrest the movement of the severing member.

This is the position shown in Fig. 4, and continued forward movement of the arm 19 moves the pin 55 below the latch dog 54, so that the severing member will be locked in this position with respect to the arm 19. Further forward movement of the latter moves the latch member 52 with it, which movement will continue until the pinion 23 strikes the stop member 42 which may be the position shown in Fig. 3 in which the latch member 52 is moved away from the member 57. It is understood that this latch member will be carried along with the arm 19 throughout the continued movement of the latter regardless of where the stop 42 may be set.

The tape will be torn off by moving it upwardly against the severing member 44 at the end of the forward movement of the arm 19, presumably in the position shown in Fig. 3. Thereafter, the arm 19 will be returned rearwardly to its original position by the spring 25. The arm 46 carrying the severing member will remain locked in position, as shown in Fig. 3, until the latch member 52 strikes against the stop 57, as shown in Figs. 4 and 5. This will arrest the movement of the latch member, and the arm 19 will continue to move rearwardly without it. At about the time that the latch member strikes the stop 57, the cam surface 50 on the arm 46 will engage the cam surface 51 and will move the arm 46 in a clockwise direction (Fig. 4) about its pivot 47 to the original position shown in Fig. 2, thus moving the severing member 44 with respect to the feed drum to expose the free end of the tape. The rearward or return movement of the arm 19 is checked by a rounded portion 65 of the arm 46 coming in contact with an arcuate edge portion 66 of the arm 29. Thus, the arm 46 serves as the stop member to limit the reverse or return movement of the feed mechanism.

When the dispensed portion of the tape is torn off against the severing member, a free end will be left which will normally be out of contact with the feed member 20. However, it may be that, in some instances, this end of the tape will become engaged with the feed drum and will not extend freely therefrom, as shown in Fig. 2. In order to insure a free projecting end which may be readily grasped by the operator, we have provided a stripping means in the form of a plurality of blades 68 which extend into the spaces between the disks 21, these stripping blades being carried by a plate 69 reciprocably mounted on the arm 19. For this purpose, the plate 69 is provided with slots 70 in which are received headed members 71 secured to the arm 19. The member 69 is cut away at its rear surface providing shoulders 72 and 73, and the tailpiece 56 of the arm 46 extends through this cut-out portion to engage these shoulders, so that the position of the stripping blades 68 is controlled by the arm 46 which carries the severing means. In the position shown in Figs. 3 and 4, for example, when the tailpiece 56 is in its lowermost position and the severing member 44 is in its forward position relatively to the arm 19, the stripping blades 68 will drop by gravity to their lowermost position.

in which the pins 71 are at the upper ends of the slots 70, so that upper ends of the stripper blades will lie below the upper periphery of the feed drum. When, however, the arm 19 is in its rearward position, as shown in Fig. 2, and the tailpiece 56 has been moved to its upward position by engagement of the cam 50 with the cam surface 51, the upper edge of the tailpiece 56 will engage the upper shoulder 72 and move the stripper blades upwardly as permitted by the slots 70, so that the upper ends of these blades will lie above the periphery of the feed drum and will assure that the free end of the tape is stripped therefrom to extend in a projected position, as shown in Fig. 2.

It is believed that the operation of the machine will be apparent from the foregoing, but may be briefly described. With the parts in the position shown in Fig. 2 in which the tape 34 has been trained about the feed drum 20, the operator grasps the free end 35 of the tape and pulls upon it in a forward direction. This tends to move the feed arm 19 forwardly, which in turn effects rotation of the drum through the engagement of the pinion 23 with the teeth of the gear rack 13. It will be apparent that the length of tape dispensed will be equal to the length of the arc through which the periphery of the feed drum 20 is rotated. It will also be apparent that the hand of the operator in drawing tape from the machine will not only be moved through this distance, but will, in addition, be moved through a distance equal to the forward movement of the arm 19. Thus, the pull of the operator will be exerted over a distance greater than the length of tape dispensed. This gives the operator an advantage in power with the result that less effort is required to strip the tape from the roll than would be required if it were done by a straight pull upon the end of the tape.

When forward movement of the arm 19 is arrested by engagement of the pinion 23 with the stop 42, the operator pulls the tape upwardly against the severing member 44 and severs the tape, the arm 46 being locked in position by the latch dog 54. At the time of the severing of the tape, the severing member 44 stands in the forward position shown in Fig. 3. When the tape is severed, the arm 19 is automatically returned to its original position by the spring 25. When the latch member 52 strikes the stop 57, the tailpiece 56 of the arm 46 is released from the latch dog 54, and the severing member 44 is moved rearwardly by the engagement of the cam surfaces 50 and 51, thus exposing the end of the tape on the feed drum. At the same time, the stripper member 68 is moved upwardly by the tailpiece 56 to insure that the free end of the tape stands in a projecting position, as shown in Fig. 2.

It will be understood that the forward movement of the severing member is effected by the spring 48, and, in like manner, upon rearward movement of the arm 19 the latch member 52 is caused to follow the arm by action of the spring 60. This spring, however, allows the arm 19 to move rearwardly independently of the latch member when the latter engages the stop 57 to release the pin 55.

While we have shown and described a preferred embodiment of our invention, it will be understood that it is not to be limited to all of the details shown, but is capable of modification and variation within the spirit of the invention and within the scope of the claims.

What we claim is:

1. A tape-dispensing machine comprising a frame, a carrier mounted for back and forth movements on the frame, rotatable tape-feeding means mounted on said carrier and having a tape-engaging peripheral surface, a severing member, means mounting said severing member on said carrier for movement relatively to the carrier, and means for locking said severing member against movement during the severing operation.

2. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier on an axis eccentric to the axis of the feeding means, means for moving said severing member forwardly relatively to the carrier upon forward movement of the latter, and means for retaining said severing member in its forward position.

3. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier on an axis eccentric to the axis of the feeding means, means for moving said severing member forwardly relatively to the carrier upon forward movement of the latter, means for retaining said severing member in its forward position, and means for disengaging said retaining means from the severing member upon rearward movement of the carrier.

4. A tape-dispensing machine comprising a frame, a carrier mounted for back and forth movements on the frame, rotatable tape-feeding means mounted on said carrier and having a tape-engaging peripheral surface, a severing member, means mounting said severing member on said carrier for movement relatively to the carrier, means for locking said severing member against movement, said locking means comprising a member mounted on the frame for back and forth movements with the carrier, and a spring normally holding said member in engagement with the carrier.

5. A tape-dispensing machine comprising a frame, a carrier mounted for back and forth movements on the frame, rotatable tape-feeding means mounted on said carrier and having a tape-engaging peripheral surface, a severing member pivotally mounted on the carrier, said severing member being disposed adjacent the tape-engaging surface of the feeding means, and means for moving said severing member relatively to the carrier upon movements of the latter.

6. A tape-dispensing machine comprising a frame, a carrier mounted for back and forth movements on the frame, rotatable tape-feeding means mounted on said carrier and having a tape-engaging peripheral surface, a severing member pivotally mounted on the carrier, said severing member being disposed adjacent the tape-engaging surface of the feeding means, said severing member normally standing in a rearward position when the carrier is in a rearward position, and means for moving said severing member forwardly relatively to the feeding means upon forward movement of the carrier.

7. A tape-dispensing machine comprising a

frame, a carrier mounted for back and forth movements on the frame, rotatable tape-feeding means mounted on said carrier and having a tape-engaging peripheral surface, a severing member pivotally mounted on the carrier, said severing member being disposed adjacent the tape-engaging surface of the feeding means, said severing member normally standing in a rearward position when the carrier is in a rearward position, and means for moving said severing member forwardly relatively to the feeding means upon forward movement of the carrier, said means comprising a spring.

8. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, means for moving said severing member forwardly upon forward movement of the carrier, and means comprising a stop fixed with respect to the frame to engage said severing means when the carrier is moved rearwardly and hold the severing means in a rearward position.

9. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier on an axis eccentric to the axis of the severing means, a stop member fixed with respect to the frame and adapted to engage said severing means to move the latter to a rearward position when the carrier is moved to a rearward position, and a spring connected to the severing means normally urging it to a forward position when the latter is disengaged from said stop member upon forward movement of the carrier.

10. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, a spring for moving said severing member to a forward position upon forward movement of the carrier, and latching means to lock said severing member in its forward position.

11. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, a spring for moving said severing member to a forward position upon forward movement of the carrier, latching means to lock said

severing member in its forward position, said means comprising a latch member pivotally mounted on the frame, and a spring urging said latch member toward the carrier.

12. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, a spring for moving said severing member to a forward position upon forward movement of the carrier, latching means to lock said severing member in its forward position, said means comprising a latch member pivotally mounted on the frame, a spring urging said latch member toward the carrier, and a stop on the frame engaging said latch member to limit the rearward movement thereof when the carrier moves rearwardly.

13. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, a spring for moving said severing member to a forward position upon forward movement of the carrier, latching means to lock said severing member in its forward position, said means comprising a latch member engageable with a part of the severing member upon forward movement of the carrier, and means for disengaging said latch from the severing member upon rearward movement of the carrier.

14. A tape-dispensing machine comprising a frame, a carrier mounted for back and forth movements on the frame, rotatable tape-feeding means mounted on said carrier and having a tape-engaging peripheral surface, a severing member pivotally mounted on the carrier upon an axis eccentric to the feeding means, said severing member being disposed adjacent the tape-engaging surface of the feeding means, said severing member normally standing in a rearward position when the carrier is in a rearward position, means for moving said severing member forwardly upon forward movement of the carrier, comprising a stop fixed with respect to the frame, to engage said severing means when the carrier is moved rearwardly and hold the severing means in a rearward position, and said stop acting to limit the rearward movement of the carrier.

15. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier for movement relatively to the feeding means, a stripper at the feeding means movably mounted on the carrier, and a lost-motion connection between said stripper and said mounting means.

16. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier, a tailpiece attached to said mounting means on one side of its pivot, a stripping member movably mounted on the carrier, and the tail piece of said mounting means being engaged with said stripping member to actuate the latter.

17. A tape-dispensing machine comprising a frame, a carrier mounted for back and forth movements on the frame, rotatable tape-feeding means mounted on said carrier and having a tape-engaging peripheral surface, a severing member, means pivotally mounting said severing member on the carrier, a tailpiece attached to said mounting means on one side of its pivot, a stripping member movably mounted on the carrier, the tailpiece of said mounting means being engaged with said stripping member to actuate the latter, and said engagement comprising a lost-motion connection.

18. A tape-dispensing machine comprising a frame, means thereon for supporting a roll of tape, a carrier mounted for back-and-forth movements on the frame, rotatable tape-feeding means mounted on said carrier, said feeding means having a tape-engaging peripheral surface, a severing member movably mounted on said carrier and disposed adjacent the tape-engaging surface of the feeding means, and means for moving said severing member relatively to the carrier, said means becoming effective to move the severing member upon a pull on the free end of the tape engaged with the surface of the feeding means.
